Inventor
FRANK M. VLCEK
By his Attorney

W. Cullen

UNITED STATES PATENT OFFICE.

FRANK M. VLCEK, OF SILVER LAKE, MINNESOTA.

FLATIRON.

Application filed November 12, 1923. Serial No. 674,364.

To all whom it may concern:

Be it known that I, FRANK M. VLCEK, a citizen of the United States, residing at Silver Lake, in the county of McCloud and 5 State of Minnesota, have invented certain new and useful Improvements in Flatirons, of which the following is a specification.

This invention relates to flat irons of the type used for pressing clothes, and the main 10 object is to provide a highly novel, practical and efficient iron adapted to be heated by an electric current and in which is incorporated a handily arranged and controlled rheostat, so that the temperature of the iron 15 can be regulated to meet the needs of the occasion and the desire of the operator.

Further objects will be disclosed in the course of the following specification, the invention being illustrated by the structure 20 shown in the accompany drawing, in which:

Fig. 1 is an elevation of the iron embodying my invention, a portion being broken away for illustration purposes.

Fig. 2 is a plan elevation as seen substantially on the line 2—2 in Fig. 1.

Fig. 3 is a sectional elevation as seen substantially on the line 3—3 in Fig. 1.

Fig. 4 is a diagrammatic view of the wiring circuit.

Referring to the drawing more particularly and by reference characters 5 designates the main casing portion of an electric iron having a handle 6, a heating element 7 and circuit closing terminals 8, all of common and well known construction.

Integrally formed upon the top of the main casing 5, and directly below the handle 6, I provide an auxiliary casing 9 having a longitudinally arranged slot 10, and 40 graduations 11 at one side of the slot. Within the auxiliary casing 9 I provide a rheostat 12 consisting preferably of a pair of resistance coils, the circuit through which is controlled by an adjusting piece 13 which 45 extends up through the slot 10 for ready access by the operator. Under one end of the slot 10 is provided an insulation member 14 which acts as a switch, as the circuit is opened when the member 13 reaches a posi-

tion correspoding therewith. It is found 50 desirable to mark upon the auxiliary casing 9 suitable temperature characters such as "Warm", "Hot", "Very hot" and "Out", so that the operator will know and can determine the actual heat condition of the iron 55 at all times.

It is understood that suitable modifications may be made in the structure as herein shown and described, provided, however, that such modifications come within the 60 spirit and scope of the appended claims.

Having now therefore fully shown and described my invention, what I claim to be new and desire to protect by Letters Patent is:

1. The combination with a flat iron, of a heating element within the iron, a rheostat arranged on the iron and in constant circuit with the entire heating element, said rheostat including circuit breaking means. 65

2. The combination with a flat iron having a handle arranged thereabove, of an electric heating element in the iron, and a rheostat arranged under the handle, and in constant circuitous relation with the entire heating element, for controlling the current thereto. 75

3. The combination with a flat iron having a handle arranged thereabove and an electric heating element arranged therewithin, of means arranged upon the iron and below the handle for controlling the current to the entire heating element. 80

4. An electric heating device, consisting of a casing having a heating element therein, an auxiliary casing arranged upon the first mentioned casing, a rheostat device within the auxiliary casing, and a handle secured to the first mentioned casing and arranged over the auxiliary casing, said rheostat being connected with opposite poles of the heating element so as to control the current to the entire heating element so that all parts thereof will be uniformly energized. 90

In testimony whereof I affix my signature.

FRANK M. VLCEK.
